WILLIAM C. CORYELL AND CLARENCE W. NOBLE, OF YOUNGSTOWN, OHIO, ASSIGNEES,
BY MESNE ASSIGNMENTS, TO TRUSCON STEEL COMPANY, OF YOUNGSTOWN, OHIO,
A CORPORATION OF MICHIGAN.

FABRICATED LATTICED GIRDER.

Application filed October 6, 1923. Serial No. 666,965.

This invention relates to girders for building construction and the like, and more particularly to an improved type of latticed girder which is fabricated from standard rolled sections.

A primary object of the invention is to provide a girder or truss construction consisting of tension and compression chord members which may be fabricated in long lengths that may be subsequently cut, bent and otherwise prepared to suit the requirements of the particular job after reaching the distant warehouse or job site. That is to say, the invention contemplates the provision of a girder construction comprising chord and truss members which for a given sized girder, will all be made in standard long lengths, adapted for one or two car length shipments, and which can be later sub-divided at the distant warehouse or construction location to suit special requirements. Girders manufactured in accordance with this practice not only minimize mill operations and handling, but also the cost of shipping and the liability of danger in making errors is reduced to a minimum by eliminating the great number of modifications which are otherwise required in the main fabricating plant.

Another object of the invention is to provide the girder construction having great load carrying capacity and strength due to the fact that the bottom chord is bent diagonally upward at its end to meet the top chord in such a way that the ends of both chords may be securely connected in a novel and practical manner at the point of support.

A further object of the invention is to provide a fabricated girder or truss construction having means for anchoring the same in the concrete in such a way as to safeguard the girder against movement in a lateral or sidewise direction.

With the above and other objects in view which will more readily appear as the nature of the invention is better understood, the same consists in the novel construction, combination and arrangement of parts hereinafter more fully described, illustrated and claimed.

A preferred and practical embodiment of the invention is shown in the accompanying drawings, in which:

Figure 1 is a detail side elevation of a portion of a fabricated girder construction in accordance with the present invention.

Figure 2 is a vertical sectional view taken on the line 2—2 of Figure 1.

Figure 3 is a vertical sectional view taken on the line 3—3 of Figure 1.

Figure 4 is a more or less diagrammatic view illustrating the manner in which a girder of the desired length can be made.

Figure 5 is a side elevation of a completed girder.

Figure 6 is a detail sectional view of the bottom chord member before the said edges thereof are crimped inwardly.

Similar reference characters designate corresponding parts throughout the several figures of the drawings.

In addition to the advantages heretofore pointed out, namely, that of minimizing manufacturing operations and the facility with which the parts of the girder may be handled, a girder constructed in accordance with the present invention has the additional advantage of being very much cheaper than girders or beams of the solid web type because rolled steel sections of the heavy type are very much cheaper per ton of steel than are the thin strips which are largely used in the construction of the solid web type of metal lumber. Also a beam of the fabricated type offers much less surface for exposure to the atmosphere than does a piece of steel lumber of equal strength and therefore in that type of beam there is a less percentage of material lost due to rust.

Referring more particularly to the novel features of the present girder construction it will be observed that the same essentially includes in its organization the top and bottom members A and B, an end coupling or filler C, and a suitable truss arrangement designated generally as D for connecting the top and bottom members between the ends. The top member A constitutes the compression chord and the bottom member B constitutes the tension chord, both of said members being of channel cross section, and preferably, although not necessarily, made from the same set of rolls.

As shown in Figure 2 the top and bottom chord members A and B are provided on their adjacent sides with the flanges 1 which form relatively deep recesses or channels 2

at the inner sides of the members, while the opposite faces may be provided with the offset ribs 3 which provide relatively shallow recesses or channels 4 at the outside faces. In connection with the ribs 3 of the upper member or top chord A it is pointed out that these ribs serve to support the metal lathing or other reinforcement a sufficient distance from the main part of the top chord so as to permit the concrete to readily flow underneath the lath or reinforcement and fill the channel or recess 4. Thus, in addition to these ribs serving as a good bearing surface for the reinforcement, they also serve to provide a key for the concrete which will prevent the beam or girder from slipping or shifting laterally or in a sidewise direction.

For the purpose of connecting the top and bottom chord members A and B at the point of support the bottom chord B is bent upwardly at an angle as indicated at B', while the extreme end or tip B² is bent parallel to the top chord A so as to permit of uniting the ends of the top and bottom members by the rolled coupling or filler block C. This block is preferably of H-shape cross section and consists of the horizontal web portion 5 and the outer vertical walls 6 which cooperate with the horizontal web to provide sockets for receiving the flanges 1—1 of the top and bottom chords as shown in Figure 2. The walls 6—6 are preferably a little narrower than the flanges 1 so that when the ends of the members are clamped together a welding pocket ω may be formed; and to enable the filler block to rigidly and securely unite the ends of the chord members the upper and lower edges of the walls 6 may be fillet welded as indicated at ω to the chords thereby providing a rigid and secure union for the top and bottom members of the girder. This construction is well adapted for taking care of the horizontal shear at the ends of the beam.

The diagonal or lattice construction D may be of any well known and standard type such for example as the Warren truss type as shown in the present drawings, or it may consist of verticals and diagonals of the type known as the Howe or Pratt trusses. In the type of truss shown in the drawings the diagonal bar members 7 preferably run in the form of a continuous letter W and are provided on their side edges with relatively short projections or lugs 8 which are irregular as to spacing and as to size and serve to act as shearing members against the tension or compression which may be brought to the top or bottom chord by the diagonal member. No instance has been found which requires that these lugs be of precise size or location. This is especially of great importance in rolling mill practice, for while the lugs can be made of a uniform

size and spacing in a newly made roll, they will not remain uniform in actual practice due to the resetting of the rolls and lack of registration at each resetting. Also from one redressing to another which occurs frequently, the diameters of the rolls will decrease from day to day and the consequent spacing of the lugs will become less and less. It will also happen that one roll may wear faster than the other of the same pair and therefore the spacing in one roll will not keep step with the spacing in the other roll. Therefore, due to continual wear on the rolls, and other conditions in rolling mill practice, the distance between the lugs becomes shorter and eventually new pockets must be machined in the rolls so as to permit proper spacing. Because of these difficulties in spacing the lugs 8, it has been found that they should be located at irregular intervals and that the relative positions of the lugs on the opposite faces of the diagonals 7 may be left to the accident of how the rolls happen to be placed at the time of attaching the spindle to the roll neck.

Referring further to the diagonals 7 of the truss D it will be observed that the relatively horizontal portions 9 thereof lie within the relatively deep channels or recesses 2 at the inside faces of the chords A and B, and are interlocked with the flanges 1 by crimping down the edges or lips of the flanges 1 as indicated at 10 thereby providing an adequate joint between the diagonal 7 of the truss and the top and bottom chords of the girder.

From the foregoing it will be apparent that the present invention makes it possible to provide a girder comprising only two or three rolled sections, and which may be easily standardized into a product of great uniformity and simplicity of construction, requiring no modification from one continuous girder to another. That is to say, the top and bottom chords A and B as well as the filler block C and diagonals D may be made in standard lengths and kept in storage until required for a particular job. At that time long sections are taken from the warehouse and fabricated in accordance with the detail specifications which are prepared for the particular job. These specifications may not be much more than a mere expression of the length and depth of the finished girder, and are, therefore, easily comprehended by workmen who become specialized and highly efficient in knowing how to prepare the sections due to the simplicity of the instruction. After the top chord has been measured and cut to the required length, the bottom chord will be cut to a greater length than the finished length of the beam by an amount determined upon by laying out the chord correctly for the offset bends which are to be made at the ends.

(Note lines S—S, Fig. 4.) The diagonal members will then be cut and bent in accordance with predetermined calculations, and then the parts may be assembled into 5 girder formation.

In connection with the novel end construction for uniting the top and bottom chords of the beam, and the diagonal lattice bar 7, it is pointed out that the upwardly bent portion B' of the bottom chord, together with the top chord and adjacent diagonal 7 constitute a triangular panel at the ends of the girder which is of great strength and load carrying capacity.

10 15 Without further description it is thought that the features and advantages of the invention will be readily apparent to those skilled in the art, and it will of course be understood that changes in the form, 20 portion and minor details of construction may be resorted to, without departing from the spirit of the invention and scope of the appended claims.

We claim:

25 1. A girder consisting of top and bottom chords spaced in parallel relation throughout the major portion of their length, a web forming truss member arranged between and attached to the parallel portions of said 30 chords, one end of one chord being deflected from a point adjacent the terminal of said truss member toward the end of the other chord and united thereto.

2. In combination, a body of concrete and 35 a girder, the latter provided with a groove in its top chord and supporting the former, a key extension of the concrete entering said groove to prevent lateral movement of the girder, relative to the concrete, and web 40 members connecting the chords.

3. A latticed girder construction consisting of top and bottom connected chord members, the top chord member being straight longitudinally throughout its length, and 45 the ends of the bottom chord member being offset towards the top chord, and a filler block rigidly joining the ends of the chord members and adapted to carry longitudinal shear.

50 4. A latticed girder construction consisting of rolled top and bottom chord members, and a zigzag panel member attached to the chords by crimping thereon the flanges of the bottom chord members, the end of said 55 girder being produced by an offset in the

bottom chord, and said chords being united at their ends by a welded joint.

5. In combination, a body of concrete, a girder including top and bottom chords formed with grooves of different depth in 60 opposite faces, a key extension of the concrete entering the top groove of the top chord to prevent lateral movement of the girder relative to the concrete, and web members connecting the chords.

6. In combination, a body of concrete, and a girder including top and bottom chord members formed with grooves of different depth in opposite faces and assembled so that the deepest grooves are arranged at adjacent faces of the members while the shallow groove of the upper bar forms a channel to receive a key extension of the concrete to prevent lateral movement of the girder, and truss members having portions lying 70 within the relatively deep grooves at the adjacent faces of the chord members and interlocked with the flanges forming the edges of said grooves.

7. In combination, a body of concrete, and 80 a built-up girder construction including top and bottom chord members provided with flanges on their top and bottom faces and also provided with other flanges on their inner faces, trussing means interlocked with 85 the flanges on the inner faces and the flanges on the outer face of the top chord being adapted to engage a key extension, of the concrete to prevent lateral movement of the girder.

8. A girder end-construction including 90 rolled channel sections for the top and bottom chord members, the end portion of the bottom chord member being deflected upwardly in proximity to the top chord member, and rolled H-sections fitting between the 95 ends of the chord members and secured thereto.

9. A girder end-construction including 100 rolled channel sections for the top and bottom chord members, the end portion of the bottom chord member being deflected upwardly in proximity to the top chord member, and rolled H-sections fitting between the ends of the chord members and welded 105 thereto.

In testimony whereof we hereunto affix our signatures.

WILLIAM C. CORYELL.
